DESIGN FOR A DISPLAY CASE

Jerry Tyler, Niles, Mich., assignor to Tyler Fixture Corporation, Niles, Mich., a corporation of Michigan

Application June 15, 1938, Serial No. 77,851

Term of patent 7 years

To all whom it may concern:

Be it known that I, Jerry Tyler, a citizen of the United States, residing at the city of Niles, in the county of Berrien and State of Michigan, have invented a new, original, and ornamental Design for a Display Case, of which the following is a specification, reference being had to the accompanying drawing, forming a part thereof.

The figure is an angular front and end perspective view of a display case showing my new design.

The end of the case not shown is similar in appearance to the end which is shown.

The back of the case is plain and bears no ornamentation.

I claim:

The ornamental design for a display case, as shown and described.

JERRY TYLER.
